ENGINE CRANKCASE

Harry S. Benjamin, Detroit, and Hallison R. De Harte, Farmington, Mich., assignors to The Leading Engine Company, Detroit, Mich., a corporation of Michigan

Application April 20, 1948, Serial No. 145,826

Term of patent 14 years

(Cl. D77—1)

To all whom it may concern:

Be it known that we, Harry S. Benjamin and Hallison R. De Harte, both citizens of the United States, residing respectively at Detroit, in the county of Wayne and State of Michigan, and Farmington, in the county of Oakland and State of Michigan, have invented a new, original, and ornamental Design for an Engine Crankcase, of which the following is a specification, reference being had to the accompanying drawing, forming a part thereof.

In the drawings:

Figure 1 is a front elevation of an engine crankcase, showing our new design;

Figure 2 is a top plan view of the engine crankcase shown in Figure 1;

Figure 3 is a left-hand side elevation of the engine crankcase shown in Figure 1;

Figure 4 is a right-hand side elevation of the engine crankcase shown in Figure 1; and

Figure 5 is a rear elevation of the engine crankcase shown in Figure 1.

We claim:

The ornamental design for an engine crankcase, as shown.

HARRY S. BENJAMIN.
HALLISON R. DE HARTE.
